ATTORNEYS

UNITED STATES PATENT OFFICE.

RUDOLPH C. G. STAATS-OELS, OF BROOKLYN, NEW YORK.

SHOE HEEL AND SOLE LIFT.

Application filed March 12, 1924. Serial No. 698,618.

To all whom it may concern:

Be it known that I, RUDOLPH C. G. STAATS-OELS, a citizen of the United States, residing at Brooklyn, county of Kings, and

5 State of New York, have invented certain new and useful Improvements in Shoe Heel and Sole Lifts, of which the following is a specification.

This invention relates to lifts for the sole 10 and heel of shoes, and has for its main object to provide means, simple in construction, effective in operation, and durable in use, adapted to give a resilient tread to the entire dorsal surface of the foot or the heel 15 or ball thereof.

A further object of the invention is to provide a resilient heel and sole lift that is not only resilient, but also pneumatic, and in which air is confined to provide a 20 cushioning effect, and in which the inherent resilience of the material forming the lift is supplemented by the cushioned air within the lift.

Another object of the invention is to provide 25 a device of the class described which not only contains air, but also contains air under initial compression, whereby the cushioning effect is constantly maintained to a maximum extent.

With the foregoing, and other objects in view, hereinafter stated, the invention consists of the novel construction, combination and arrangement of parts hereinafter more specifically stated, and illustrated in the 30 accompanying drawings, wherein is shown a device embodying the structure of the invention in its preferred form, but it is to be understood that changes, variations and modifications may be resorted to without departing from the scope of the invention.

In describing the invention in detail, reference is had to the accompanying drawings, which form a part of this specification, and wherein like characters of reference indicate corresponding parts throughout the several views, and wherein:

Fig. 1 is a vertical section of a heel lift embodying the invention in one of its forms 45 as arranged when applied to a shoe indicated in dotted lines.

Fig. 2 is a vertical section of the parts forming the heel lift shown in Fig. 1, arranged in partial engagement with each other.

55

Fig. 3 is a plan of the tread surface of the lift shown in Fig. 1.

Fig. 4 is a plan view, partly broken away, of a sole lift embodying the invention.

Fig. 5 is a longitudinal central section 60 of the sole lift, shown in Fig. 4, partly broken away, and

Fig. 6 is a fragmentary section of the outer margin and connecting portion of a lift, embodying a modification of the invention.

As illustrated in the drawings the heel lift is constructed of an attaching section 1 and a tread section 2. The section 1 is provided with a marginal flange 3, offset 70 from the margin of the section, and engaging a marginal flange 4 of the tread section 2, and a step 5, on the outer margin of the tread section, said flanges together forming the outer wall of the lift.

75

The flat bearing surfaces of the sections are spaced from each other intermediate the outer wall and are provided with complementary bosses, 6 and 7, which bear against each other at their ends, as shown in Fig. 80 1, forming bearings between the flat surfaces of said members intermediate the outer margins thereof and at the same time maintaining a hollow chamber intermediate the sections.

85.

The ends of the bosses are preferably constructed to engage each other and to that end one of the bosses 7 is recessed as at 8 to provide means for engaging the end of the opposite section 6.

90

Recesses 9 are formed in the flat bearing surfaces and in the bosses of the attaching section to a point removed from the end thereof, and corresponding recesses 10 are formed in the tread section, which is also 95 provided with a recess 11 for the insertion of the head of a nail.

When the parts are so constructed, the attaching section or male member of the heel is brought into engagement with the 100 tread or female section, by bringing the margin of the flange 3 into engagement with

that of the flange 4 as shown in Fig. 2. The air then confined between the two sections is compressed to a limited extent, as the two sections are brought together as shown 5 in Fig. 1.

The side walls of the sections when brought together are cemented together, and are firmly secured by the extended bearing and holding surfaces comprising the side 10 and end surfaces of the engaging flanges.

From the foregoing description, taken in connection with the drawings, the construction, operation and advantages of the heel lift will clearly appear.

15 It will be seen that a lift is provided that may be made of resilient material, preferably rubber and that the lift is provided with an air chamber so constructed that air is entrapped within the chamber, while the 20 sections of the lift are being brought into engagement with each other, and is maintained within said chamber under sufficient pressure to maintain the lift in an inflated condition, thereby giving to the user not 25 only the benefit of the inherent resiliency of the rubber material forming the body of the lift, but also the benefit of the air cushion formed in the lift.

The invention as embodied in a sole lift 30 is shown in Figs. 4 and 5, in which the lift is constructed of an attaching section 12 and a tread section 13.

As shown in Fig. 5 the attaching section 12 is provided with a marginal rib 14, which 35 engages a corresponding recess formed in the adjacent part of the tread member 13, to form a locking engagement between said sections.

Means may be provided of any suitable 40 construction for limiting the movement of the tread surface 12, relative to the attaching section.

In the drawings such means consist of transverse ribs 15 and connecting ribs 16. 45 The upper surface of said ribs being preferably but not essentially arranged in the plane of the outer surface of the ribs 14.

The sections of the sole lift are brought 50 together in a manner similar to the sections of the heel lift. As the outer margin of the rib 14 comes in contact with the wall of the recess in the tread section, a certain amount of air is confined within the hollow interior of the lift and when the outer walls 55 of the sections are cemented together, the air is maintained within said interior, and is compressed to a limited extent, causing or tending to cause the tread surface of the lift to bulge slightly outward, as indicated 60 by the dotted line in Fig. 5.

As illustrated in Fig. 5 the outer margin 65 of the tread section is reduced by means of a marginal recess or step 16, formed thereon. That is not an essential feature of the invention, however, and if desired, the outer

margin of the tread section may be made flush with the tread surface of the section as shown in Fig. 6.

Where the outer margin of the tread section is reduced as shown in Figs. 4 and 5, 70 the toe end of the lift may be provided with a wearing plate 17, which may be set into and secured to the reduced marginal toe portion of the lift, by means of nails 18 or otherwise.

The lift may be secured to the sole of a shoe by means of a row of stitching along the outer margin of the lift, or by other means, and for some purposes the lift may 75 be used as the sole of a shoe.

By means of such construction, a lift or sole is provided that is simple and strong in structure, and durable in use and which provides a soft yielding tread for the foot, and avoids the heating effect produced by 80 heavy rubber soles, for the reason that the air cushion prevents heat from being transmitted to the foot of the user in the summer time.

Such construction also prevents cold from 85 passing to the foot of the user in the winter time, the air cushion serving as a non conductor.

In the constructions shown in Figs. 1 and 2, bosses are formed on both the attaching 90 and tread sections. Such construction may be modified if desired, and the bosses formed on one of the sections only as shown in Fig. 5.

In the construction shown in Fig. 5, moreover, the ribs 15 and 16 may normally be extended so as to be in close proximity to the inner surface of the tread section.

Instead of the ribs 15 and 16, shown in Figs. 4 and 5, bosses similar to those indicated in Figs. 1 and 2 or modifications thereof may be used.

While the heel lift is shown herein as made independently of the sole lift, that is not an essential feature of the invention 100 and if desired both of said lifts may be made integral with each other.

In Figs. 1 and 2 the bosses, when in contact, are of substantially the same length. In some cases, however, it is preferable to make the bosses of the male section 1 longer than those of the female section 2, so that bosses of the male section may engage the bosses of the female section at the same time the marginal flange 3, of the male section engages the marginal flange 4 of the female section 2, and when so constructed the openings 9 of the bosses for the attaching nails may be formed entirely through the bosses.

What I claim as new and desire to secure by Letters Patent, is:

1. A resilient lift for heels comprising complementary sections provided with marginal flanges cemented together and having 120

on their inner faces engaging bosses provided with closed ends and with nail apertures extending from said closed ends to the outer surface of said sections.

5 2. A resilient lift for shoes having complementary sections provided with engaging side walls cemented together, one of said sections having a plurality of bosses provided with a nail aperture and a closed 10 end, said sections and walls forming an air chamber within said lift.

3. A resilient lift for heels including complementary sections capable of engagement at their outer margins and recessed in 15 their adjacent faces to provide an air chamber interiorly of said lift, and bosses extending from said faces into engagement with

each other, said bosses having closed ends and apertures extending outwardly from said ends.

4. A resilient lift for heels including complementary sections capable of engagement at their outer margins and recessed in their adjacent faces to provide an air chamber interiorly of said lift, bosses extending from 20 said faces into engagement with each other, said bosses having closed ends and apertures extending outwardly from said ends, and one of said bosses having a recess into 25 which extends a portion of the other boss 30 when the bosses are engaged.

In testimony whereof I have affixed my signature.

RUDOLPH C. G. STAATS-OELS.
